CONSTANT PRESSURE SYSTEMS

Bernhardt Joseph Eiseman, Wilmington, Del., assignor to E. I. du Pont de Nemours and Company, Wilmington, Del., a corporation of Delaware

No Drawing. Application July 18, 1955
Serial No. 522,877

4 Claims. (Cl. 252—62)

This invention is directed to a process for reducing the change of pressure in a closed essentially fixed-volume system, said change in pressure being due to temperature variations.

Constant pressure systems have utility as reference sources in automatic devices where pressure changes activate compensating mechanisms. For example, in an automatic installation actuated by pressure changes, a constant pressure system would be incorporated in a Wheatstone bridge type of electronic control circuit. Another application of a constant pressure system is to be found in a fixed-volume system where temperature changes and resultant difference in inside and outside pressure would normally cause deformation of the physical materials comprising the periphery of the system.

The latter type application of a constant pressure system, in a fixed volume, is exemplified in present day refrigerators and cold storage boxes. It is known that the use of fibrous insulation between the interior and exterior walls of a refrigerator for all practical purposes eliminates convection and radiation losses; however, a factor which causes inefficiency of said insulation system is gaseous conduction. At the present time, the gaseous material between the walls of the refrigerator is air. It is known, however, that gaseous conduction is inversely proportional to the square root of the molecular weight of the gas (other things being equal and the mean free path being small compared to the interstices) and it becomes apparent that by use of gases heavier than air a more efficient insulating system would result.

In order to more advantageously use a gas between the interior and exterior walls of a refrigerator, the gas must not only have a molecular weight higher than that of air, but said gas should also be non-flammable, non-toxic, relatively inexpensive, and available commercially. Fluorinated hydrocarbon gases have an obvious advantage over air for such use since they have the characteristics just enumerated.

It is an object of this invention to provide a process for maintaining a constant pressure system which will effect efficient insulation for refrigeration and thermal insulation panels. It is a further object of this invention to reduce the change of pressure over a range of temperatures in a closed fixed-volume system thus increasing the insulating capacity of said system in addition to making possible the use of economical design and lighter construction materials.

In the present day refrigerators, the air-filled insulation is vented to maintain the air at the ambient pressure. When using fluorinated hydrocarbon gases, it is necessary to utilize a sealed system; however, in such a system differences in pressure between said system and the ambient air will develop on heating or cooling. In the ordinary refrigerator and freezer, inside temperatures will range from 40° C. during storage to —40° C. during use which temperature differences may cause as much as 5 lbs. per square inch pressure variation and can result in excessive buckling or other damage to the thin metal wall of the

2

refrigeration panels. This buckling and deformation could be prevented by re-inforcing the walls of the system, but such a technique would increase the cost and also decrease insulating efficiency because of increased heat conduction.

5 The closed systems just described are useful not only for refrigerator systems but also for thermal insulation panels generally. The use of a fluorinated alkane gas to reduce gaseous conduction in such panels has the added advantage of enabling the use of thinner panels to result in more 10 efficient thermal insulation.

The process of the present invention for maintaining constant pressure systems which will avoid the problems above-discussed, is accomplished by maintaining in a closed fixed-volume system a gaseous phase and a liquid phase, said gaseous phase comprising a fluorine-containing halogenated alkane and said liquid phase comprising a saturated equilibrium mutual solution of a crystallizable organic solid and a fluorine-containing halogenated alkane, said solution containing not more than 10 mole percent of gaseous fluorinated alkane.

20 The fluorine-containing halogenated alkanes useful for the gaseous phase in the process of this invention are readily available well known compounds. Said alkanes may be straight chained or cyclic and may contain halogens other than fluorine. The selection of the particular fluoroalkane to be used will depend upon the temperature range to be encountered and the pressure over which the particular system is to operate. In addition, the fluoroalkane will be selected in conjunction with the crystallizable organic solid to be used in the system. Furthermore, the selected gaseous fluorinated alkane must have a solubility, in its mutual solution with the organic solid, which will not exceed about 10 mole percent. If this solubility limit is greatly exceeded, an inoperable system will result.

30 Examples of fluorinated alkanes which will be of value as the gaseous phase of the constant pressure system are: fluorotrichloromethane, dichlorodifluoromethane, chlorotetrafluoromethane, dichlorofluoromethane, chlorodifluoromethane, trifluoromethane, chlorofluoromethane, chloropentafluoroethane, hexafluoroethane, pentafluoroethane, bromochlorodifluoromethane, bromotetrafluoromethane, bromodifluoromethane, bromopentafluoroethane, perfluorocyclobutane and the like.

40 The solid which is incorporated with the fluoroalkane in the fixed-volume system may be selected from a wide variety of organic compounds providing these compounds meet the following qualifications:

- 45 (1) They must be mutually soluble with the fluorinated alkane gas to form a liquid solution.
- (2) They must crystallize out of their mutual solution with the fluoroalkane.
- (3) They must not chemically react with the gaseous component.

55 By solid, it is meant that the substance is a solid under conditions of use. Nitrobenzene for example, normally a liquid, melts at 5.6° C., but is an operable solid in systems which function at temperatures somewhat above 6° C. and below. As discussed later, the system can be operated at temperatures somewhat above the melting point of the solid in order to extend the effective temperature range.

60 Preferably the crystallizable solids will be members of the class of halogenated aliphatic hydrocarbons, aromatic hydrocarbons, and halogenated aromatic hydrocarbons. Specific examples of these preferred classes include the fluorine-containing halogenated alkanes such as 1,1-difluorotetrachloroethane, and 1,2-difluorotetrachloroethane; aromatic hydrocarbons such as benzene, naphthalene, beta-methylnaphthalene; halogenated aromatic hydrocarbons such as p-dichlorobenzene, o-chlorobiphenyl, beta-chloronaphthalene, and p-bromotoluene; less preferably, nitrated aromatic hydrocarbons such as nitro-

benzene, alpha-nitronaphthalene, and meta-nitrotoluene. As with the selection of the fluorinated alkane, the crystallizable organic solid will be chosen on the basis of the temperature range over which the fixed-volume system is to be used. Normally a solid is selected that will have a melting point about 5 to 10° C. lower than the maximum temperature of the range over which the system is to operate. For example, to maintain an essentially constant pressure in a fixed-volume system over a range of temperatures from about 0° C. to 35° C., a crystallizable organic compound would be selected having a melting point of from about 25 to 30° C. Then a fluorinated alkane gas is selected having a boiling point below 0° C. and whose solubility in its mutual solution with the crystallizable organic solid lies between about 0.5 to 10 mole percent under the conditions of use. The system is established by charging it with the organic solid and then introducing the gaseous fluorinated alkane to the desired pressure. Preferably, no more than about 10 percent of the total volume will be occupied by the condensed phase. Systems in which the liquid phase occupies more than 10 per cent of the total volume of the system are operable and useful, but it is desirable that the liquid phase occupy the smallest possible volume.

The operable temperature range may be extended by using mixtures of crystallizable organic solids and/or mixtures of gases. An additional technique for temperature range extension is to use mixtures of solids which give partially miscible or immiscible liquid phases with their mutual solution of the gas.

Performance is best when equilibrium is maintained so that the mutual liquid solution of gas and solid is saturated with respect to the solid as well as the gas. That is, there will normally be three phases within the fixed-volume system in which the pressure is to remain essentially constant. There will be a vapor phase due to the fluorine-containing alkane itself, a solid phase comprising the solid crystallizable organic compound and a liquid phase comprising the liquid mutual solution of gaseous alkane and solid organic compound. The temperature range over which the system normally operates can be extended somewhat by going beyond the region in which three phases are coexistent, but this can be done only as long as tolerable pressure changes are not exceeded.

The process of this invention functions by virtue of the fact that the mutual solution of fluorinated alkane and crystallizable organic compound serves as a buffer against pressure changes due to temperature effects. As the temperature decreases, the pressure of a fixed-volume gaseous system would normally decrease. However, in the system described herein, a temperature decrease also causes the organic compound to crystallize out of its mutual solution and as a result, the fluorinated alkane is evolved as vapor, its increased amount thus compensating for the pressure drop due to the temperature decrease. Conversely, when the temperature rises, the solid organic compounds melts, thus decreasing the concentration of gas in the mutual solution and allowing more gas to dissolve, which in turn offsets the expected pressure increase due to the temperature rise.

For the present system to be operable, the solubility of the fluorinated alkane in the crystallizable organic solid should be less than 10 mole percent. If this solubility limit is exceeded, the system fails to function properly; this failure is due to the fact that the solubility of the gas in its mutual solution is so great that the gas is not evolved when the liquid is concentrated by crystallizing out solid on temperature reduction. Since gas is not evolved, the pressure falls and the system is no longer constant pressure.

The gaseous alkane must have some minimum solubility with the solid in order for the system to function. This lower limit will depend on the particular choice of

components, but will be within the range of 0.5 to 1 mole percent.

In the present invention it is desirable that the liquid phase occupy the smallest possible volume. It has been observed that in the process of this invention, the liquid phase will normally occupy less than 10 percent of the total volume of the system. In insulated panels, for example, the liquid phase may be absorbed through the fibrous ceramic materials (such as "rock" or "mineral" or "glass" wool) used inside said panels; this will provide a large surface area and will add in maintaining equilibrium conditions. The condensed phase will distill or sublime onto the colder wall and form a layer over the large area which will serve to prevent conduction through the insulation by the condensed phase of the system.

The process of this invention will normally enable a fixed-volume system, as described, to maintain a pressure not varying more than about 10 percent over the range of temperatures desired. Also significant, however, is the fact that the novel systems of this invention permit control of pressure changes even over rather small temperature ranges. In this latter instance, the expected pressure change due to a change in temperature may be within 10% of the original pressure, but by use of the process of this invention the actual pressure change may be reduced to a small fraction of the expected change. Where large easily deformed surfaces are exposed to even small pressure changes, this control will be particularly valuable, since even small pressure changes can greatly affect large unsupported areas. The process is not limited to any particular pressure and may be applied to subatmospheric as well as superatmospheric pressures, although in most practical applications, the process will be used to maintain an essentially constant pressure which falls within 10 to 100 lbs./sq. in. absolute. Preferably, the process will be used at about 10 to 20 lbs./sq. in. absolute; i. e., at about atmospheric pressure where it will find utility in insulation systems.

EXAMPLE 1

A fixed-volume system was constructed from a length of glass tubing of about 1 inch diameter, closed at one end and fitted at the other end with a closure leading to a valved opening and a pressure gauge. The total volume of this system, including pressure gauge and the closed valve was 211 cc. The system was maintained upright and a mark made on the glass tube to indicate a volume of 153 cc. from the bottom of the tube to the mark.

The system was opened by removing the top closure and 9.1 grams of beta-methylnaphthalene were introduced into the tube as the crystallizable organic solid. The top was replaced, the tube immersed in liquid nitrogen and the valve at the top closure connected to a vacuum pump. When the pressure inside the system was reduced to 0.01 mm. Hg, the valve was closed, and the pump removed. The tube was then removed from the liquid nitrogen bath and warmed to 32° C. (rm. temp.) by immersing it up to the mark in a water bath. Bromotrifluoromethane gas was then introduced through the valve at 32° C. until saturation was reached at 2.5 p. s. i. g. As the gas was added, the solid phase inside the tube decreased and liquid phase appeared. When 2.5 p. s. i. g. was reached, about 7 mole percent of the gas was in solution and the condensed phase occupied about 6% of the volume up to the mark and only a trace of solid remained.

The system was shown to maintain an essentially constant pressure by varying the temperature of the water bath and noting, by means of the gauge, the small change in pressure that actually occurred. The table which follows indicates the small pressure change with varying temperature:

5
Table I

Bath temp., ° C.	Pressure in P. S. I. A.
35.6	16.7
35.4	16.9
33.9	17.0
32.0	17.5
30.0	17.6
25.2	17.8
22.5	17.9
19.2	17.8
14.8	17.6
9.2	17.3
4.5	17.1
2.5	16.9
0	16.8
-5.2	16.6
-10.0	16.4
-15.0	16.0

Calculations by the gas laws show that the temperature decrease would be expected to reduce the pressure of the system from 16.7 p. s. i. a. at 35.6° C. to 13.9 p. s. i. a. at -15° C.

EXAMPLE 2

Following the details of Example 1, the system was charged with 4.8 parts of beta-methylnaphthalene and dichlorodifluoromethane gas was added to a saturation pressure of 2.8 p. s. i. g. at 29° C. There was about 7 mole percent of gas in solution and the condensed phase of the system occupied 3.2% of the volume up to the mark. The table which follows indicates the slight change in pressure over the temperature range of 35° C. to -15° C.

Table II

Temperature of system, ° C.	Pressure in P. S. I. A.
35.0	17.8
32.0	17.6
30.0	17.5
29.0	17.5
27.5	17.6
25.0	17.7
21.0	18.2
18.0	18.7
15.7	19.0
14.5	19.0
10.2	18.8
7.0	18.7
5.0	18.5
2.0	18.4
0	18.2
-4.5	18.0
-7.8	17.7
-10.0	17.6
-12.5	17.3
-15.0	17.1

According to gas law calculations, the pressure at -15° C. is expected to be 14.9 p. s. i. a.

EXAMPLE 3

Using the apparatus and procedure of Example 1, a system was prepared from 8.1 grams 1,1-difluorotetrachloroethane as solid and gaseous bromotrifluoromethane pressured into the system at 32° C. to a saturation pressure of 17.2 p. s. i. a. There was about 5 mole percent of gas in solution and the condensed phase occupied about 3% of the volume up to the mark. On varying the bath temperature, the following data were obtained:

Table III

Bath tem- perature, ° C.	Pressure of system, P. S. I. A.
34.0	17.2
30.5	16.7
29.5	16.7
26.2	18.5
25.0	18.5
20.0	18.0
15.5	17.6
10.0	17.1
4.0	16.7
0	16.5

6
EXAMPLE 4

As in Example 1, the tube was charged with 10.6 grams of 1,2-difluorotetrachloroethane and chlorotrifluoromethane charged into the system to a saturation pressure of 17 p. s. i. a. at 24.2° C. There was about 3 mole percent of gas in solution and the condensed phase occupied about 4% of the volume up to the mark. The following table illustrates the effectiveness of the system over a temperature range:

10

15

Table IV

Temperature of system, ° C.	Pressure of system, P. S. I. A.
28.0	17.5
26.8	17.5
25.0	17.1
22.5	16.9
21.0	17.5
20.2	17.9
18.0	17.9
15.0	17.8
12.5	17.7
10.0	17.6
7.8	17.5
5.0	17.2
2.0	16.8
-1.0	16.7

EXAMPLE 5

30 The table which follows describes several additional systems which will maintain a pressure of about 15 p. s. i. a. over the range of temperatures indicated:

Table V

35	Solid (M. P. °C.)	Gas	Approx. percent of total vol- ume occu- pied by condensed phase	Mole per- cent of gas in sol. at 1 atm. pres- sure and at maxi- mum tem- perature	Temp. range, °C., over which 15 p. s. i. a. will be main- tained
40					
	Naphthalene (79.5)--- p-Dichlorobenzene (53)	CBrF ₃ CBrF ₃	9.2 2.5	0.65 0.84	+90 to +30 +60 to +30
45	Nitrobenzene (5.6)--- Naphthalene (79.5)---	CBrF ₃ CCl ₂ F ₂	4.2 3.8	1.3 1.2	+10 to -30 +83 to +38

EXAMPLE 6

Following the procedure of Example 1, 39.2 parts of beta-methylnaphthalene are introduced in a fixed-volume system and after evacuation is pressured with a mixture of gases comprising 3.1 parts of CCl₂F₂ and 0.5 part by weight of CBrF₃. Approximately 10% of the total volume of the system is occupied by the condensed phase and about 4 mole percent of the gases is in solution at 1 atmosphere and at 35° C. This system will maintain a pressure of essentially 15 p. s. i. a. over a temperature range of from +35 to -10° C.

EXAMPLE 7

60 A mixture of crystallizable organic solids can be employed as follows:

A mixture of 23 parts of naphthalene and 40 parts of p-dichlorobenzene (melting point of solid mixture=29° C.) is placed in a constant volume system and after 65 evacuation the system pressured with 1.1 parts by weight of CBrF₃. About 1.2 mole percent of the gas dissolves at 1 atmosphere pressure and at 35° C. and the condensed phase occupies about 9% of the total volume of the system. When the system is subjected to temperatures between 35 and -10° C., the pressure of the system remains essentially at 15 p. s. i. a.

EXAMPLE 8

75 The operating range of the system described in Example 7 can be extended to higher temperatures by

adjusting the composition of the mixture of crystallizable organic compounds so that it has a higher melting point. By charging the system with a mixture comprising 11.4 parts of naphthalene and 51.4 parts of p-dichlorobenzene (melting point of mixture=41° C.) and pressuring the evacuated system with 0.8 part of CBrF_3 so that 0.8 mole percent of the gas is in solution and the condensed phase occupies 10% of the total volume, the system maintained a pressure of essentially 15 p. s. i. a. over a temperature range of 50 to -10°C .

EXAMPLE 9

An essentially constant pressure system can be prepared in which two immiscible liquid phases are used. Using 34 parts of 1,4-butanediol and 17.5 parts of beta-methylnaphthalene as the crystallizable solids, charging the system with 1 part of CBrF_3 so that 0.8 mole percent of gas dissolves at 15 p. s. i. a. and at 40°C . and the two immiscible condensed phases obtained occupy 19% of the total volume, a system is obtained which maintains an essentially constant pressure of 15 p. s. i. a. over temperatures from $+45^{\circ}\text{C}$. to -5°C .

EXAMPLE 10

The beta-methylnaphthalene of Example 9 is replaced with 18 parts of nitrobenzene. The system is pressured with CBrF_3 at $+20^{\circ}\text{C}$. and 15 p. s. i. a. until 0.7 mole percent is in solution and the two immiscible liquid phases obtained occupy about 22% of the total volume. In this way a system is obtained which will maintain an essentially constant pressure of 15 p. s. i. a. over the temperature range of $+20$ to -40°C .

Another application of the constant pressure systems of this invention is in those instances where volume changes have a thermal effect such as in a liquid spray system wherein a liquefied gas vaporizes and thus expands to displace a diaphragm or piston which in turn forces liquid through a spray nozzle, said system being activated by a valve which opens the system to the atmosphere. When open to the atmosphere, the liquefied gas vaporizes and a temperature drop results; said drop in temperature reduces the vapor pressure of the liquefied gas and thus reduces the pressure acting upon the diaphragm or piston. If constant pressure is maintained in spite of this thermal effect, a more efficient system would result.

This invention provides a constant pressure system in such applications, since by its use the thermal effect of

vaporization or condensation of the gas is offset. This results from the fact that although the temperature tends to drop on the vaporization of the liquefied gas, the solid crystallizes out which tends to raise the temperature because of the heat of crystallization of the solid. The latter offsets the cooling effect and the pressure remains essentially constant. Components of high purity should be used since any impurities present may accumulate in the liquid phase and lower the vapor pressure. Solids which readily form supersaturated solutions should be avoided.

In these systems, constant pressure with varying ambient temperature, as above described, is also desirable.

I claim:

1. A process for reducing changes in pressure, said pressure being within the range of 10 to 100 p. s. i. a. in a closed essentially fixed-volume system subjected to varying temperatures within the range of 90°C . to -40°C ., said temperatures within said range varying from about 50°C . below the melting point of the crystallizable organic solid to about 10°C . above said melting point, which process comprises maintaining in said system a gaseous fluorine-containing halogenated lower alkane of from 1 to 4 carbon atoms and a liquid saturated equilibrium mutual solution of a crystallizable organic solid taken from the group consisting of halogenated aliphatic hydrocarbons, 1,4-butanediol, aromatic hydrocarbons, halogenated aromatic hydrocarbons, and nitrated aromatic hydrocarbons, and, said fluorine-containing halogenated alkane, said fluorine-containing halogenated alkane being present in said mutual solution in the amount of about 0.5 to about 10 mole percent, said crystallizable organic solid being mutually soluble with and chemically inert to said gaseous fluorinated alkane, and, said organic solid being crystallizable out of said mutual solution.

2. The process of claim 1 in which the gaseous fluorine-containing halogenated alkane is a gaseous mixture of said fluorine-containing halogenated alkanes.

3. The process of claim 1 in which the crystallizable organic solid is a mixture of said crystallizable organic solids.

4. The process of claim 1 wherein about 10% of the total solution of said system is occupied by said mutual solution.
